UNITED STATES PATENT OFFICE

CARL THORBECKE, OF NACKENHEIM, GERMANY

LIMED BANDAGE OR RING FOR FRUIT TREES AND THE LIKE

Application filed March 19, 1930, Serial No. 437,134, and in Austria April 15, 1929.

The invention relates to an improved limed bandage or ring for fruit trees and the like, which is intended to prevent caterpillars and other pests from ascending the 5 trunk of the tree.

The limed bandage or ring according to the invention consists of two strips of material, such as paper or the like, of different widths, each of which strips is provided on 10 one side with a continuous layer of adhesive material, such as lime for catching caterpillars, the layers of adhesive material being of equal width and extending longitudinally along the central portion of the strip, and the 15 strips being arranged one above the other, in such manner, that the two layers of adhesive material register exactly with one another, whereby a double band is formed which has no adhesive material on its external 20 surface and the wider strip of which projects at its two longitudinal edges beyond the narrower strip at a suitable distance therefrom over its whole length, so as to render it possible to affix the broader strip in 25 one working operation by means of its two longitudinal edges. The double strip formed in this manner may be rolled up and preserved in a cardboard sheath.

A limed bandage or ring, constructed according to the invention, is illustrated, by way of example, in the accompanying drawing, in which:

Fig. 1 shows a tree trunk to which the broader strip of the limed bandage has already been affixed by means of string, the figure illustrating the operation of drawing off the narrower strip.

Fig. 2 shows the limed bandage in elevation, and

Fig. 3 in cross section.

The limed bandage or ring consists of two strips *a* and *b* of different widths. Each strip is provided on one side at its central part with a layer of adhesive material, such as lime for catching caterpillars. The two strips *a* and *b* are arranged one above the other (see Fig. 3) in such manner that their limed layers *c* register exactly with one another. In this way a double strip is obtained having longitudinal borders which are free

from adhesive material, and by means of which the bandage is tied on to the trunk of the tree. As soon as the operation of affixing the winder strip has been completed and the person handling the bandage has both hands 55 free, the narrower strip *b* may be then drawn off and affixed in similar manner to the next tree trunk by binding it with string around the borders which are free from adhesive material. The double strip above described 60 is rolled up and preserved in a cardboard sheath or box.

The limed bandage, according to the invention, has the advantage that two limed strips are provided in the form of a double 65 strip, in such manner as to render it possible to affix each bandage in one working operation, whilst entirely preventing the hands being rendered dirty during the operations of handling the said bandage. 70

I claim:

1. A limed bandage for fruit trees and the like comprising in combination: a strip of material, a layer of adhesive material extending longitudinally along the central portion of said strip on one side thereof, a second strip of material of less width than said first-named strip, and a layer of adhesive material of the same width as said first-named layer extending along the central 75 portion of said second strip, said strips being arranged one above the other so that their layers register exactly with one another, whereby a double band is formed which has no adhesive material on its external surface and the said wider strip of which projects at its two longitudinal edges beyond the narrower strip at a suitable distance therefrom over its whole length. 85

2. A limed bandage for fruit trees and the 90 like, comprising in combination: a strip of paper; a layer of lime for catching caterpillars arranged on one side of said strip and extending longitudinally along the central portion of said strip over its whole length; a second strip of paper of less width than said first-named strip, and a second layer of lime for catching caterpillars, arranged on one side of said second strip and extending longitudinally along the central 95 portion of said second strip. 100

tion of said second strip over its whole length; said strips being arranged one above the other so that their layers register exactly with one another, whereby a double band is formed which has no lime on its external surface and the said wider strip of which projects at its two longitudinal edges beyond the narrower strip and a suitable distance therefrom over its whole length.

10 Signed at Frankfort-on-Main, Germany,
this 1st day of March, 1930.

CARL THORBECKE.
